SMOKE CONDITIONER FOR TOBACCO PIPES

George W. Webb, Los Angeles, Calif.

Application April 21, 1937, Serial No. 138,196

5 Claims. (Cl. 131—204)

This invention relates to and has for an object an improved moisture absorbing and smoke conditioning member for a tobacco pipe, wherein the member may be conveniently removed from the pipe and detached from the mouth piece upon withdrawing or detaching said mouth piece from the pipe stem and without requiring fingering of said member.

Another object is to provide a tobacco pipe attachment or accessory of the character described in the form of an absorbent pad adapted to be wrapped on or arranged to at least partially encompass a portion of the mouth piece which is telescopically fitted with the pipe stem whereby to form a substantially tubular absorbent member which will take up and retain the moisture in the pipe, insure better combustion of the tobacco, prevent withdrawal of the moisture through the mouth piece and improve the quality of the smoke, it being noted that the smoke passes through the bore of the tubular member instead of being filtered through the moisture and nicotine laden material of said member.

A further object is to provide a moisture absorbing pad of the character described and will either automatically unwrap and become detached from the mouth piece upon detachment of the latter or be subject to detachment by effecting a quick, downward snap motion of the mouth piece when the latter is removed from the pipe stem.

Another object is to provide a moisture absorbing pad of the character described, having means thereon adapted to be engaged by the mouth piece so as to insure the proper positioning of the pad when inserting the mouth piece, and also insure withdrawal of the pad when the mouth piece is withdrawn from the stem.

I have shown in the accompanying drawing a preferred form of a smoke conditioner for tobacco pipes embodying my invention, subject, however, to modification, within the scope of the appended claims, without departing from the spirit of my invention.

In said drawing:

Fig. 1 is a longitudinal sectional view of a pipe having the smoke conditioner of this invention incorporated therewith,

Fig. 2 is an end elevation of the smoke conditioner when rolled into tubular form,

Fig. 3 is a side elevation of said conditioner,

Fig. 4 is a fragmentary side elevation of the

portion of the mouth piece which is telescoped by the pipe stem,

Fig. 5 is a bottom plan view of said conditioner when in slit form,

Fig. 6 is a side elevation of the blank from which the clip is formed,

Fig. 7 is a top plan view of the clip blank as shown in Fig. 6,

Fig. 8 is a front elevation of the finished clip,

Fig. 9 is a side elevation of the finished clip,

Fig. 10 is a top plan view of the finished clip, and

Fig. 11 is a fragmentary perspective view showing the manner in which the conditioner detaches itself from the mouth piece upon withdrawal of the latter from the pipe stem.

Fig. 12 is an enlarged longitudinal section showing the relationship of the clip to the mouth piece and pad of absorbent material.

One embodiment of this invention comprises 20 a conditioning member in the form of a piece or pad 1 of absorbent material, said piece of material or pad being adapted to be wrapped on or otherwise arranged to at least partially encompass the portion 2 of the mouth piece 3 so as 25 to be positioned within the stem 4 of the pipe 5 when said mouth piece is fitted within the stem. The pad or piece of absorbent material may be made of paper or any other suitable substance and when wrapped around or otherwise mounted 30 on the mouth piece takes a substantially tubular form whereby to permit the free passage of smoke through the bore yet absorb and retain the moisture accumulating in the pipe. By providing for the passage of smoke through the 35 "bore" of this substantially tubular absorbent member instead of filtering the smoke through the material, the smoke is not contaminated by the moisture and nicotine saturated material.

As here shown the portion 2 of the mouth 40 piece which fits into the stem 4 is formed as a spirally grooved member having one end provided with a bore 6 and embedded in the mouth piece. The mouth piece has the usual bore or smoke passage 7 which registers with the bore 6 45 and the latter communicates by means of the passage 6' with the spiral groove of the member 2 so that the smoke will pass freely through the stem and mouth piece. However it is to be understood that the absorbent smoke conditioning 50 means of this invention is applicable to any type of mouth piece which is fitted into the pipe stem and provides for the passage of smoke through the bore created by the tubular formation of said member.

In order to provide for detachment of the absorbent member from the mouth piece without fingering said member and upon removal of the mouth piece from the stem, said member is positioned on the mouth piece so that it will unwrap itself or come apart and fall from the mouth piece upon withdrawal of the latter from the stem. However should the absorbent member, by retaining its tubular form, adhere to the mouth piece when the latter is withdrawn from the stem, the dislodgement of said member may be readily effected with a downward, snapping motion of the mouth piece.

To insure the removal of the absorbent member with the mouth piece when the latter is detached from the stem, means is provided for detachably engaging said member and mouth piece so that the frictional contact of the member with the stem will not prevent its withdrawal with the mouth piece. Any means for detachably connecting the member with the mouth piece which will positively withdraw the member upon detachment of the mouth piece from the stem, may be used.

As here shown this means comprises a small clip 8 having an attaching tongue 9 adapted to pierce the member 1 as indicated in Figs. 2 and 3, or otherwise suitably engaged with said member for affixing the clip thereto. This clip is also provided with spaced tongues 10 in the form of teeth adapted to engage with the portion 2 of the mouth piece. In the present instance the teeth 10 will engage in one of the grooves of the portion 2 of the mouth piece so that when the mouth piece is removed from the stem the absorbent member will be pulled out with it.

If the pad is made of a sheaf of papers the tongue 9 in being extended through said sheaf serves the purpose of holding the sheaf together as well as fixing the clip in place. It should be noted that the clip is of arcuate cross-section so that it will readily conform to the curvature of the portion 2 around which the pad or member 1 is wrapped.

It should be noted that the clip holds the absorbent member against slipping, relative to the mouth piece when inserting the latter into the stem so as to insure the proper positioning of the absorbent member into the stem and the retention thereof in such position. The smoke conditioner of this invention is also applicable to smoking devices other than pipes, such as cigar and cigarette holders.

I claim:

1. A smoke conditioning and moisture absorbing means for tobacco smoking devices comprising a substantially tubular piece of absorbent material adapted to be positioned upon a portion of the mouth piece of the smoking device, which portion is inserted in the stem of said device, said

portion having a smoke conducting groove therein and a clip adapted to engage in said groove without obstructing the passage of smoke therethrough and to engage with said tubular member for detachably connecting the latter with said portion, whereby said tube may be inserted into and removed from the stem together with said portion. 5

2. A tobacco smoking device having a detachable mouth piece, a portion of said mouth piece 10 extending into an enlarged bore in a stem of the device, the diameter of said bore being greater than the diameter of said portion, a smoke conditioning and moisture absorbing member comprising a piece of absorbent material adapted to 15 be fitted in a substantially cylindrical shape to the outside of said portion, and means providing for the insertion and removal of said member relative to the stem, said means including a clip effective to connect said portion and said member when the latter is held in its cylindrical shape and to release said member when the latter is unfolded from its cylindrical shape, said portion providing a passage for smoke between it and the interior surface of said cylindrical 20 member. 25

3. A moisture absorbing member for a tobacco smoking device comprising a piece of absorbent material adapted to be fitted in a substantially cylindrical form to the outside of that portion of 30 the mouth piece of a smoking device which is inserted in the stem of said device, whereby smoke will contact with the interior surface of said cylindrically fitted piece, and a clip engaged with and disposed between said interior surface 35 and said portion of said mouth piece for effecting the insertion and removal of said cylindrically fitted absorbent piece relative to said stem.

4. A moisture absorbing member for a tobacco smoking device comprising a piece of absorbent 40 material adapted to be fitted in substantially cylindrical form to the outside of that portion of the mouth piece of a smoking device which is inserted in said stem of the device and a clip fixed to said piece so as to be disposed upon the 45 interior surface thereof when said piece is fitted as aforesaid, for effecting the insertion and removal of said piece with said portion.

5. A moisture absorbing means for a tobacco pipe comprising an absorbent member adapted 50 to be positioned upon a portion of the mouth piece of the pipe which is inserted in the stem of the pipe, said member taking the form of a tube providing for the passage of smoke through the bore thereof, and a clip fixed to said member 55 and disposed interiorly of the bore formed by said member for engagement with said mouth piece for effecting the insertion and removal of said member with said mouth piece.

GEORGE W. WEBB. 60
